VIBRATOR MACHINE

Louis G. Coury, Passaic, N. J.

Application October 4, 1949, Serial No. 119,544

2 Claims. (Cl. 128—33)

1

This invention relates to vibratory therapeutic machines, and more particularly to a vibrator of the platform type adapted to impart vibrations to the human body for the purpose of stimulating the blood circulation, relieving nervous or muscular tension, and for otherwise relieving bodily or psychological disturbances or discomforts.

A main object of the invention is to provide a novel and improved vibratory platform device upon which a person may stand and be given a treatment of a vibratory nature, said device being very simple in construction, including means for controlling the amplitude of the vibrations, and requiring very little maintenance.

A further object of the invention is to provide an improved vibrator of the platform type, said vibrator being relatively inexpensive to manufacture, being rugged in construction, being relatively quiet in operation and requiring only a relatively small driving means.

Further objects and advantages of the invention will become apparent from the following description and claims, and from the accompanying drawings, wherein:

Figure 1 is a front elevational view of a vibratory machine constructed in accordance with the present invention;

Figure 2 is a top plan view of the machine of Figure 1;

Figure 3 is a vertical cross-sectional view taken on line 3—3 of Figure 1;

Figure 4 is a vertical cross-sectional view taken on line 4—4 of Figure 3;

Figure 5 is an enlarged vertical cross-sectional detail view taken on line 5—5 of Figure 4;

Figure 6 is a fragmentary horizontal cross-sectional view taken on line 6—6 of Figure 1;

Figure 7 is an enlarged elevational detail view of one of the rotating weight elements carried by the shaft of the motor of the machine of Figure 1;

Figure 8 is a cross-sectional view taken on line 8—8 of Figure 7;

Figure 9 is an enlarged cross-sectional detail view taken on line 9—9 of Figure 3;

Figure 10 is an enlarged cross-sectional detail view taken on line 10—10 of Figure 2;

Figure 11 is an enlarged cross-sectional detail view taken on line 11—11 of Figure 3;

Figure 12 is a schematic wiring diagram of the motor circuit employed in the machine of Figure 1.

Referring to the drawings, 11 designates a rectangular shell secured at its bottom portion on a plate member 12 provided with the supporting feet 13 located adjacent the respective corners of the plate member. The rear wall of the shell 11 is designated at 14, and rigidly secured to said rear wall are the vertical arms 15, 15 of an upstanding, inverted, U-shaped, tubular support member 16. The top arm of the member 16 is

2

shown at 17, and serves as a hand rail, as will be subsequently described.

As shown in Figures 3 and 4, the rear wall 14 of shell 11 is reinforced at the connections of the arms 15, 15 thereto by a pair of horizontal angle bars 18, 18 through which the bolts 19, 19, securing the arms 15, 15 to the wall 14, pass.

The angle bars 18, 18 may be secured in addition to the rear wall 14 by other bolts 20, 20.

Designated at 21 are respective cylindrical spring members, preferably of solid rubber or similar resilient material, the lower portions of the members 21 being secured in receptacles 22 provided with depending axial studs 23. Secured to the respective side walls of the shell 11, shown at 24, 24, are a pair of angle brackets 25, 25, the depending studs 23 of each of the receptacles 22 passing through the horizontal arm of a bracket 25 and being rigidly secured thereto by a nut 26. Each of the solid spring members 21 extends a substantial distance above the top plane of the shell 11 and has embedded in its upper portion an internally-threaded, axial insert 27. Designated at 28 is a plate member secured to the respective solid springs 21 by machine screws 29 threadedly engaging the inserts 27. The top surface of the plate member 28 is provided with a resilient rubber pad 30 fastened thereto by any suitable means. Designated at 31 is an electric

motor suspended beneath and rigidly secured to the plate member 28 at its central portion, as by a pair of hanger brackets 32, 32, clampingly surrounding the motor housing, as shown in Figures 3 and 4.

35 The motor shaft is shown at 33 and projects axially from the motor at opposite ends thereof. Secured to the respective ends of the shaft 33 are the arms 34, 34, each arm being formed with an enlarged weight ball 35, said weight balls being substantially in longitudinal alignment.

As shown in Figures 7 and 8, the arms 34 are rigidly secured to the shaft 33, as by transverse bolts 36 passing through the arms 34 and the shaft 33 and secured by nuts 37. The radial distances of the weight balls 35 from the shaft 33

45 are the same for each of the weight balls, and when the motor 31 is energized, the weight balls 35, 35 rotate in synchronism and develop synchronous centrifugal forces acting on the shaft 33 and through the motor 31 and its brackets 32 on the plate 28, causing said plate to oscillate vertically as the shaft 33 rotates.

As shown in Figure 11, the shell 11 is braced at its corners by vertical angle bars 38 welded to the shell at said corners, thereby making the shell 11 very rigid.

As shown in Figure 10, the resilient pad 30 may be securely clamped to the plate 28 by corner screws 39 passing through washers 40 bearing on the resilient pad 30, said screws being threadedly engaged in the plate 28.

As shown in Figure 9, the supporting feet 13 are preferably made of rubber or similar resilient material, and are provided with threaded inserts 41 in which are engaged the shanks of fastening screws 42 passing through the plate member 12.

Transversely secured to the upper portions of the vertical arms 15, 15 are horizontal bars 43, 43 to the intermediate portions of which is secured a rectangular housing member 44 containing a rheostat whose shaft projects through the front wall of the housing 44 and has mounted thereon a knob 45. The front wall of the housing 44 is provided with a scale plate 46 suitably calibrated, the knob 45 being provided with a pointer 47 movable over the calibrations of the scale plate 46.

As shown in Figure 12, the motor 31 has connected to one of its terminals a line wire 48 and to the other of its terminals a wire 49. Wire 49 is connected to the movable tap of the rheostat, shown at 50, and connected to the end terminal of rheostat 50 is a line wire 51. The wire 49 extends upwardly from the shell 11 and enters the housing 44 through its lower wall, whereas the wire 51 passes through the lower wall of the housing 44 and enters the right-hand, tubular arm 15, as viewed in Figure 1, and then passes downwardly through said tubular arm, entering the housing 11 through the lower portion of the arm 15 and the rear wall 14 of the housing, as shown in Figure 5. The wires 48 and 51 are joined to define a two-wire line cord 52 which emerges from the housing 11 through the bottom wall 12 of said housing.

As shown in Figure 12, the rheostat 50 is in normal open-circuit position, wherein the movable tap of the rheostat disengages from the winding thereof and whereby the motor 31 is normally de-energized. In operation, the person using the machine stands on the platform defined by plate 28 and pad 30, holding the rail 17 and energizes motor 31 by rotating knob 45 so that the movable tap of the rheostat engages the end of the rheostat winding. Since most of the rheostat winding is in series with the motor 31 at this point, the motor rotates at relatively low speed, thereby providing a low amplitude and slow speed of vertical oscillation of the platform. To increase the amplitude and speed of vertical oscillation of the platform, the knob 45 is rotated so as to cut out more of the winding of the rheostat 50. It is thus seen that the amplitude of oscillation of the platform may be regulated by adjusting the knob 45, the degree of adjustment being indicated by the pointer 47 in conjunction with the scale plate 46.

It will be apparent that the rail 17 will be relatively stationary, while the motor 31 is energized, since the shell 11 is cushioned with respect to the oscillating platform 28 through the solid rubber springs 21. Therefore, the person employing the machine may support himself while undergoing a vibratory treatment by grasping the horizontal rail 17. At the end of the period of treatment, the person undergoing such treatment merely rotates the knob 45 so that the pointer 47 is moved to the "off" position, whereby the motor 31 becomes de-energized.

While a specific embodiment of a vibratory therapeutic apparatus has been disclosed in the foregoing description, it will be understood that various modifications within the spirit of the invention may occur to those skilled in the art. Therefore, it is intended that no limitations

be placed on the invention except as defined by the scope of the appended claims.

What is claimed is:

1. In a platform vibrator having a hollow rectangular base, a rectangular platform disposed at the upper side of said base, a motor secured to said platform at the under side thereof and depending into said base, said motor including a shaft, and weights eccentrically carried by the motor shaft for imparting vibration to said platform upon rotation of the motor shaft, means resiliently mounting said platform on said base comprising angle brackets secured to said base one near each corner thereof and projecting inwardly of the base, upwardly opening receptacles secured one on each bracket, solid blocks of resilient material disposed at the under side of said platform within said receptacles, an internally screw threaded insert in each block at the end thereof adjacent said platform, and screws extending through corresponding apertures in said platform and threaded into the corresponding inserts to secure said blocks to said platform, said blocks being received at their ends remote from said platform by corresponding cups carried by said brackets.

2. In a platform vibrator having a hollow rectangular base provided with a bottom wall and an open upper side, a rectangular platform disposed at the upper side of said base, a motor secured to said platform at the under side thereof and depending into said base, said motor including a shaft, and weights eccentrically carried by the motor shaft for imparting vibration to said platform upon rotation of the motor shaft, means resiliently supporting said base and resiliently mounting said platform on said base comprising solid blocks of resilient material disposed at the outer side of said bottom wall and one near each corner of said base, a screw threaded insert in each block at the end thereof adjacent said bottom wall, screws extending through corresponding apertures in said bottom wall and threaded into said inserts to secure said blocks to the bottom wall of said base, angle brackets secured to said base one near each corner thereof above said bottom wall and projecting inwardly of the base, upwardly opening receptacles secured one on each bracket, solid blocks of resilient material disposed at the under side of said platform, an internally screw threaded insert in each of said last mentioned blocks at the end thereof adjacent said platform, and screws extending through corresponding apertures in said platform and threaded into corresponding inserts in the last mentioned blocks to secure such blocks to said platform, said last mentioned blocks being received at their ends remote from said platform by corresponding receptacles carried by said brackets.

LOUIS G. COURY.
